Primary Examiner — John Windmuller*(74) Attorney, Agent, or Firm* — Clause Eight IPS; Michael Catania**CLAIM**

The ornamental design for a set of antennas, as shown and described.

DESCRIPTION

FIG. 1 is a top plan view of a set of antennas showing our new design;

FIG. 2 is a side elevation view thereof;

FIG. 3 is a side elevation view thereof;

FIG. 4 is front elevation view thereof;

FIG. 5 is a rear elevation view thereof;

FIG. 6 is a top perspective view thereof;

FIG. 7 is a top perspective view thereof; and,

FIG. 8 is a top perspective view thereof.

The broken lines in the drawings represent environment that forms no part of the claimed design.
